SAFETY CUTOUT SWITCH

Benjamin H. Clare, Wellsville, Mo.

Application June 3, 1949, Serial No. 96,838

5 Claims. (Cl. 200—161)

1

This invention relates to an improved safety cutout switch, especially but not necessarily for use in automobile electrical systems, to provide efficient and convenient means of quickly and easily disconnecting an electrical system from its current source, such a battery, to protect the system against short circuit damage or other undesirable condition, while inactive, and upon the occurrence of an emergency.

The primary object of the invention is to provide a switch of the above character having novel construction and relative arrangement and coaction of component parts, whereby the action of the switch is rendered more efficient and reliable.

Another important object of the invention is the provision of an inexpensive and rugged switch of the above indicated character which involves relative movement of a minimum number of simple, long-lived parts.

Other important objects and advantageous features of the invention will be apparent from the following description and appended drawings, wherein, merely for present purposes of illustration, a specific embodiment of the invention is set forth in detail.

In the drawings:

Figure 1 is a vertical longitudinal section, showing the switch in closed position, and taken along the line 1—1 of Figure 2.

Figure 2 is a horizontal section taken through the upper part of Figure 1.

Figure 3 is a longitudinal section taken along the line 3—3 of Figure 2.

Figure 4 is a transverse vertical section taken along the line 4—4 of Figure 3; and

Figure 5 is a perspective view of the cover.

Referring in detail to the drawings, the illustrated switch, generally designated 1 comprises an angle bracket 8 adapted to be secured to a support, such as the firewall 9 of an automobile, with horizontal arm 10 supportably engaging the underside of the switch housing, whereby the housing is mounted in the engine compartment or other suitable place.

The switch housing comprises a rectangular block 12 of insulated material, which is centrally traversed near one end by vertical mounting bolts 13, 13 passing through the arm 10 of bracket 8. The underside of the block 12 is covered by an insulating sheet or plate 14 overlying the bracket arm 10 and serving to conceal and insulate the otherwise exposed head of a bolt hereinafter described.

As shown in Figures 1 and 2, the end of the

2

top of the block 12 remote from the attaching or mounting bolts 13, 13 is overlaid by a pair of transversely elongated conductive plates 15 and 16 which extend substantially the full width of the block and having contiguous edges electrically spaced. The plates 15 and 16 are each secured in place by a screw 17 threaded through the middle thereof into the block 12. In addition, each of the plates 15 and 16 has secured thereto corresponding binding posts 18, 19, respectively, the post 18 serving to connect the ground strap or cable 10 to the plate 15, and the post 19 serving to connect the plate 16 to cable 21 of the starter motor or the like. The posts 18 and 19 traverse their plates and are threaded into the block 12 whereby the plates 15 and 16 are locked against shifting relative to the block 12 and relative to each other. The binding posts 18 and 19 are located along the opposite longitudinal edge of the block 12 from the circuit making and breaking mechanism.

This mechanism comprises an assembling nut and bolt unit 22 whose bolt 23 is threaded upwardly through the block 12, as shown in Figure 1, with its head 24 flush with the underside of the block and concealed and protected by the insulating plate 14. Overlying both of the plates 15 and 16 and reaching toward the left in Figures 1 and 2 beyond the plate 15, is the flat relatively flexible contactor strip or bar 25 traversed by the bolt 23 and having a positioning flange 26 on its right hand end engaging the contiguous edge of the plate 16 to prevent lateral displacement of the bar 25.

The right hand portion of the bar 25 is longitudinally overlaid by a strong leaf spring 27 also traversed by the bolt 23 with a spacer 28 intervening between the bar 25 and the spring 27. A depending heel flange 29 on the spring 27 engages the spacer to preclude lateral shifting of the spring 27. A downwardly bowed toe 30 on the free end of the spring 27 bears downwardly upon the contactor bar 25 with sufficient force to assure positive and reliable bridging contact of the bar 25 with both of the contact plates 15 and 16. A spacer 29' overlies the spring 27 on the bolt 23, and a nut 23' is turned down on the bolt 23 against the spacer 29' to secure the associated parts in assembled relation.

The free end of the contactor bar 25 has an upturned bifurcated spiral 31 providing journals for transverse rollers 32, 32 on a pin 33 fixed at the elbow 34 of a vertically positioned belcrank lever 35, the lower end of whose lower short arm carries a transverse pin 36 journaling rollers 37,

37 on opposite sides of the arm to roll upon the upper surface of the block 12.

The longer upper arm of the lever 35 has an insulating extension 38 telescoped thereon and having on one side thereof at its upper end a rotatable connector 39 for the pull rod or wire 40, working through a flexible conduit 41 secured through the instrument panel 42 or the like and terminating in a knob 43.

The movement of the belcrank lever 35, in a plane perpendicular to and longitudinal with respect to the block 12 and contactor bar 25, is guided by a slot 44 in the top of a cover 45, secured over one side of block 12, which serves also to enclose and protect the make and brake mechanism and the underlying area of the top of the block 12. The other side of the top of the block 12 is left uncovered.

The box-like cover 45 is elongated rectangular in form and includes a depending flange 46, 46' on one side and its ends to engage corresponding ends and a side of the block 12 to which the flange is secured by screws 47, 47' threaded into the block.

With the operating knob 43 pushed in, as shown in Figure 1, the belcrank lever is tilted toward the right hand end of the slot 44 and the spring 27 keeps the contactor bar 25 in bridging relation to the contact plates 15, 16 thereby establishing a circuit between the battery cable 20 and the service cable 21. When the knob 43 is pulled out, the lever 35 is tilted toward the left hand end of the slot 44, thereby causing the rollers to roll upon the top of the block 12 toward the right, whereby the axis of the journal 32 is elevated and the free end of the contactor bar flexed upwardly enough to remove the contactor bar 25 from bridging contact with the contact plates 15 and 16, thereby breaking the circuit between the battery cable 20 and the service cable 21. To restore the circuit, the knob is returned to its pushed in position.

What is claimed is:

1. A safety cutout switch comprising an insulated block adapted to be mounted on a support, a pair of transversely extending contact plates secured to the top of said block in spaced airgap relation, conductor connecting means at one end of each of said plates, a make and break assembly overlying the opposite ends of said plates, said assembly comprising a flexible contactor bar mounted on said block at one end near one of said contact plates with its opposite end free, means electrically connecting said one plate to said contactor bar, said contactor bar overlying said one contact plate and the other contact plate with its free end reaching beyond said other contact plate, spring means mounted on said block near said one contact plate and urging said contactor bar into engagement with and bridging relation to both of the contact plates, a vertical lever having a roller on its lower end bearing upon the top of said block near the free end of said contactor bar, and pivot means pivotally connecting the free end of said contactor bar to an intermediate part of said lever whereby said lever can be swung in a vertical plane in one direction to roll said roller upon the top of said block and thereby displace said pivot means upwardly from the top of said block so as to flex said contactor bar upwardly out of bridging relation to said contact plates.

2. A safety cutout switch comprising an insulated block adapted to be mounted on a support, a pair of transversely extending contact plates secured to the top of said block in spaced airgap

relation, conductor connecting means at one end of each of said plates, a make and break assembly overlying the opposite ends of said plates, said assembly comprising a flexible contactor bar mounted on said block at one end near one of said contact plates with its opposite end free, means electrically connecting said one plate to said contactor bar, said contactor bar overlying said one contact plate and the other contact plate with its free end reaching beyond said other contact plate, spring means mounted on said block near said one contact plate and urging said contactor bar into engagement with and bridging relation to both of the contact plates, a vertical lever having a roller on its lower end bearing upon the top of said block near the free end of said contactor bar, and pivot means pivotally connecting the free end of said contactor bar to an intermediate part of said lever whereby said lever can be swung in a vertical plane in one direction to roll said roller upon the top of said block and thereby displace said pivot means upwardly from the top of said block so as to flex said contactor bar upwardly out of bridging relation to said contact plates, said spring means comprising a leaf spring longitudinally overlying said contactor bar having a free end bearing upon the top of said contactor bar, and common means mounting said leaf spring and said contactor bar on said block.

3. A safety cutout switch comprising an insulated block adapted to be mounted on a support, a pair of transversely extending contact plates secured to the top of said block in spaced airgap relation, conductor connecting means at one end of each of said plates, a make and break assembly overlying the opposite ends of said plates, said assembly comprising a flexible contactor bar mounted on said block at one end near one of said contact plates with its opposite end free, means electrically connecting said one plate to said contactor bar, said contactor bar overlying said one contact plate and the other contact plate with its free end reaching beyond said other contact plate, spring means mounted on said block near said one contact plate and urging said contactor bar into engagement with and bridging relation to both of the contact plates, a vertical lever having a roller on its lower end bearing upon the top of said block near the free end of said contactor bar, and pivot means pivotally connecting the free end of said contactor bar to an intermediate part of said lever whereby said lever can be swung in a vertical plane in one direction to roll said roller upon the top of said block and thereby displace said pivot means upwardly from the top of said block so as to flex said contactor bar upwardly out of bridging relation to said contact plates, said lever consisting of a belcrank with said pivot means located at the junction of the arms of said belcrank.

4. A safety cutout switch comprising an insulated block adapted to be mounted on a support, a pair of transversely-extending contact plates secured to the top of said block in spaced airgap relation, conductor-connecting means at one end of each of said plates, a make-and-break assembly overlying the opposite ends of said plates, said assembly comprising a flexible contactor bar mounted on said block at one end near one of said contact plates with its opposite end free, means electrically connecting said one plate to said contactor bar, said contactor bar overlying said one contact plate and the other contact plate with its free end reaching beyond said

other contact plate, spring means mounted on said block near said one contact plate and urging said contactor bar into engagement with and bridging relation to both of the contact plates, a vertical lever provided with movable bearing means on its lower end movably bearing upon the top of said block near the free end of said contactor bar, and pivot means pivotally connecting the free end of said contactor bar to an intermediate part of said lever, whereby said lever can be swung in a vertical plane in one direction to move said movable bearing means upon the top of said block and thereby displace said pivot means upwardly from the top of said block so as to flex said contactor bar upwardly out of bridging relation to said contact plates.

5. A safety cutout switch comprising an insulated block adapted to be mounted on a support, a pair of contact plates secured to the top of said block in spaced relation, conductor connecting means carried by each of said plates, a make-and-break assembly overlying said plates, said assembly comprising a flexible contactor bar mounted on said block and having one end portion thereof electrically connected to one of the 25 plates and overlying the plates, the other end

portion of said contactor bar extending beyond the other plate, spring means urging said contactor bar into engagement with and bridging relation to both of the contact plates, a vertical lever provided with movable bearing means on its lower end movably bearing upon the top of said block near the free end of said contactor bar, and pivot means pivotally connecting the free end of said contactor bar to an intermediate part of said lever, whereby said lever can be swung in a vertical plane in one direction to move said movable bearing means upon the top of said block and thereby displace said pivot means upwardly from the top of said block so as to flex said contactor bar upwardly out of bridging relation to said contact plates.
